SPINNING TOY

Jan Heim, New York, N. Y.

Application July 3, 1951, Serial No. 15,754

Term of patent 7 years

(Cl. D34—15)

To all whom it may concern:

Be it known that I, Jan Heim, a citizen of no country, residing in New York city, county of New York, and State of New York, have invented a new, original, and ornamental Design for a Spinning Toy, of which the following is a specification, reference being had to the accompanying drawing, forming part thereof, wherein;

Figure 1 is a front perspective view of a spinning toy showing my new design.

Figure 2 is a top plan view thereof, with a portion of the string member omitted from each side of the article, for convenience of illustration.

The other side of the toy not shown is substantially like the side shown.

The lining on the drawing is for contrasting color.

I claim:

The ornamental design for a spinning toy, substantially as shown and described.

JAN HEIM.
